(57) **CLAIM**

The ornamental design for case for alternatively containing or supporting a laptop computer, as shown and described.

DESCRIPTION

FIG. 1 is a perspective view from rear of case for alternatively containing or supporting a laptop computer showing my design;

FIG. 2 is a top plan view thereof;

FIG. 3 is a front elevation view thereof;

FIG. 4 is a rear elevation view thereof;

FIG. 5 is a left side elevation view thereof, the right side elevation view thereof being a mirror image;

FIG. 6 is a bottom plan view thereof; and,

FIG. 7 is a perspective view thereof in open condition.

The broken lines in FIGS. 3, 4 and 6 represent unclaimed portions of the structure and the broken lines in FIG. 7 represent an unclaimed interior file pocket.

1 Claim, 7 Drawing Sheets
